PADLOCK

Filed March 26, 1928

Harry Williams
Inventor

S. E. Thomas
Attorney

UNITED STATES PATENT OFFICE.

HARRY WILLIAMS, OF DETROIT, MICHIGAN.

PADLOCK.

Application filed March 26, 1928. Serial No. 264,730.

My invention relates to an improvement in padlocks shown in the accompanying drawings and more particularly described in the following specification and claims.

5 This invention is more especially designed as a lock for spare tires and is used in conjunction with a chain—not shown—for encircling the tire.

The primary object of this invention is to 10 provide a simple, inexpensive and effective key lock adapted to enter the links of a chain, shackle or other like device, the construction being such that the ends of the shackle are concealed in the barrel of the lock where 15 they are secured by a transversely movable bolt actuated through the operation of a key.

With the foregoing and other objects in view which will appear as the description proceeds, the invention further resides in the 20 combination and arrangement of parts and in the details of construction hereinafter described and claimed, it being understood that changes may be made in the precise embodiment of the invention herein disclosed without departing from the spirit of the same.

In the drawings accompanying this specification:

Figure 1 is a side elevation of the lock with the ends of the locking shackle concealed 30 within the barrel of the device as when locked.

Figure 2 is a longitudinal sectional view through the lock—with parts broken away—and the shackle in locked position.

35 Figure 3 is an end elevation of the lock showing the cap covering the key opening released, and the shackle in unlocked position.

Figure 4 is a longitudinal sectional view 40 showing the shackle unlocked and the cap covering the end of the barrel in open position.

Figure 5 is a fragmentary perspective view 45 showing the longer end of the shackle with a stop pin limiting its withdrawal movement, also the slotted guide bushing, rigidly secured in the barrel of the lock.

Figure 6 is a cross-sectional view taken on or about line 6—6 of Figure 4, showing the 50 bayonet groove in the central plug of the lock barrel for locking the longitudinally movable bolt upon engaging the legs of the shackle.

Figure 7 is a cross-sectional view taken on or about line 7—7 of Figure 4, showing the 55 vertically slotted bushing through which the

stop pin carried by the long leg of the shackle slides.

Referring now to the letters of reference placed upon the drawings:

A denotes a lock barrel fitted at one end with a cap B rigidly secured to the barrel. C indicates a bushing secured by a driving fit in the end of the lock barrel, having a central opening C¹ to receive one end of a longitudinally movable bolt D, provided at its opposite end with a plunger D^a,—formed with an annular rim d integral therewith.

E denotes a shackle, one leg of which is longer than the other, and extends transversely through the wall of the lock barrel,—and also through a transverse opening C² in the bushing C.

Projecting from the long leg of the shackle E is a short pin e adapted to bear against the wall of the lock barrel to preclude the removal of the shackle. To accommodate the pin e, the bushing C is provided with a transverse slot C³ and is also counterbored at C⁴ that the pin e on the long leg of the shackle may not interfere with the shackle upon being unlocked, or of rotating the shackle when in unlocked condition—see Figures 4 and 5.

The short leg of the shackle is provided with a groove E¹ to receive the annular flange d of the plunger D^a carried by the bolt D,—see Figure 2,—and is also recessed—see E²—at its lower end to straddle the bolt D when locked. The bolt D has a flange d¹ with a spring F coiled on the bolt bearing against the flange d¹ at one end and at the other end against the bushing C.

G is a lock cylinder of the usual type of construction, located at the closed end of the lock barrel. H is a longitudinally movable and rotatable plug extending through a central opening in the end wall of the lock barrel having the usual narrow slot H¹ to receive the key employed in this type of lock.

H² is an angular shaped peripheral groove in the outer face of the center plug to receive the projecting end of a pin G¹, mounted in the wall of the lock cylinder.

I denotes a cap fitted with a felt or rubber lining, I¹ adapted to cover the end of the lock barrel to guard against moisture or dirt entering the key slot. Secured to the wall of the cap I is an inwardly projecting pin J extending into an opening A¹ bored in the wall of the lock barrel.

Sleeved upon the pin J is a spring K adapted to bear at one end against the wall of the

lock barrel and at the other against a head or nut J^a on the end of the pin, the object being to yieldingly permit the withdrawal of the cap I from the end of the barrel against 5 the tension of the spring and that it may be turned to the side to gain access to the lock for the insertion of the key—see Figure 3.

Having now indicated the several parts by reference letters, the construction and operation 10 of the device will be readily understood.

In describing the operation of the device, it will be assumed that the bolt is in the unlocked position indicated in Figure 4 of the drawings, the short leg of the shackle E being 15 withdrawn from the lock barrel and free to swing as indicated in Figure 3.

To lock the device the short leg of the shackle is forced into the opening at the side of the lock barrel until the long leg strikes 20 the lower wall of the lock barrel, the short leg at the same time contacting with the bolt D ,—limiting its further movement. The key is then inserted in the opening provided in the center plug of the lock barrel and the plug 25 thereby crowded back against the plunger D^a , forcing the latter's peripheral flange into the slot E^1 in the short leg of the shackle and against the outward thrust of the spring F coiled upon the bolt.

30 When the center plug is forced back so that its outer face is flush with the outer wall of the lock barrel, the pin G^1 in the lock cylinder will be at the end of the longitudinal portion of the right angle slot H^2 , in the center plug. 35 The plug is then rotated by the key so that the pin G^1 may enter the transverse portion of the slot as clearly indicated in Figure 2—thus locking the plug against outward movement occasioned by the thrust of the 40 spring F carried by the bolt. This operation results in maintaining the peripheral flange d of the plunger D^a in the groove E^1 of the shackle, which it has now entered—the end of the bolt D simultaneously entering the 45 opening E^a in the long leg of the shackle, thereby locking the shackle in closed position.

The cap I is then rotated from the position shown in Figure 4, that it may fit over the 50 end of the lock barrel, as shown in Figure 2, the action of the spring K serving to retain the cap on the end of the barrel against accidental release or dislodgement, thereby providing a water-tight seal covering the key 55 slot and protecting the slot from exposure to the weather.

To release the locking shackle the cap I is again shifted to the position indicated in Figure 3. The key is then inserted in the key 60 slot provided in the center plug and the latter is turned so that the pin G^1 will register with the longitudinal portion of the slot in said plug, thereby releasing the plug that it may be forced outwardly by the expansion of the 65 spring F , thus freeing the plunger D^a and

the bolt D from engagement with the legs of the shackle and unlocking the device, as indicated in Figure 4.

Having thus described my invention what I claim is:

1. In a device of the character described, a lock barrel; a longitudinally slidable bolt fitted at one end with a plunger having an annular flange; a bushing secured to the lock barrel having a central bore to receive the end of the bolt; a transversely disposed shackle having one leg relatively longer than the other, each leg having a recess respectively adapted to receive the end of the bolt and the flange of its plunger; resilient means adapted to force the bolt of the plunger outwardly; a lock cylinder secured to the lock barrel; a rotatable and longitudinally movable key plug concentrically mounted in the lock cylinder in longitudinal axial alignment with the plunger, whereby upon applying pressure to the key plug the bolt with its plunger may be pushed into locking engagement with the legs of the shackle against the outward thrust of the bolt and plunger; and means for maintaining the bolt and plunger in locked relation with the legs of the shackle. 70 75 80 85 90 95

2. In a device of the character described, a lock barrel; a longitudinally slidable bolt fitted at one end with a plunger having an annular flange; a bushing secured to the lock barrel having a central bore to receive the end of the bolt and a transverse bore to receive the leg of a shackle; a shackle having one leg relatively longer than the other, the longer leg extending into the transverse bore of the bushing, each leg having a recess respectively adapted to receive the end of the bolt and the flange of its plunger; a stop pin projecting from the long leg of the shackle into a transverse slot provided in the bushing, adapted upon contacting with the wall of the lock barrel to arrest the withdrawal of the shackle from the lock barrel; resilient means adapted to force the bolt plunger outwardly; a lock cylinder secured in the lock barrel; a rotatable and longitudinally movable key plug concentrically mounted in the lock cylinder in longitudinal axial alignment with the plunger, whereby upon applying pressure to the key plug the bolt with its plunger may be pushed into locking engagement with the legs of the shackle against the outward thrust of the bolt and plunger; and means for maintaining the bolt and plunger in locked relation with the legs of the shackle. 100 105 110 115 120

3. In a device of the character described, a lock barrel; a bolt fitted with a plunger at one end and longitudinally slidable within the lock barrel; a bushing secured to the lock barrel with a central bore to receive the bolt; a shackle having one leg relatively longer than the other, each leg having a recess respectively to receive the end of the bolt and the flange of its plunger; resilient means 125 130 135

adapted to force the bolt plunger outwardly; a lock cylinder secured in the lock barrel; a rotatable and longitudinally slid able key plug concentrically mounted in the lock cylinder adapted to bear at its inner end upon the bolt plunger, said key plug provided with a peripheral right angle groove; and a pin supported in the wall of the cylinder with a projecting end extending into the right angle 5 groove of the key plug, whereby upon inserting a key the plug may be forced longitudinal-

ly against the outward thrust of the bolt and plunger that they may respectively enter into locking engagement with the legs of the shackle, whereupon the plug may be rotated 15 in the lock cylinder, causing the pin to follow the transverse portion of the groove, to secure the bolt in its interlocking relation with the shackle until released.

In testimony whereof, I sign this specification.

HARRY WILLIAMS.
